UNITED STATES PATENT OFFICE.

THOMAS J. BUSH, OF LEXINGTON, KENTUCKY.

ATTACHMENT FOR GAS-BURNERS.

SPECIFICATION forming part of Letters Patent No. 645,416, dated March 13, 1900.

Application filed June 18, 1899. Serial No. 720,773. (No model.)

To all whom it may concern:

Be it known that I, THOMAS J. BUSH, a citizen of the United States, and a resident of Lexington, in the county of Fayette, State of Kentucky, have invented a certain new and useful Improvement in Attachments for Gas-Burners, of which the following is a specification.

My invention relates to an attachment for ordinary gas-burners of the types known as the "bat-wing" and the "fish-tail" and which produce what I herein term a "flat" flame.

It is well known that the efficiency of a gas-burner of certain capacity depends largely upon the draft given the flame and the amount of oxygen infused into it.

The principal object of my invention is to provide an attachment without the use of a chimney whereby a flat gas-flame may be furnished with ample draft, thereby steadyng the flame, increasing the illuminating capacity, and decreasing the amount of smoke or carbon deposit emitted in burning.

To these ends my invention consists in the various novel and peculiar combinations and arrangements of the several parts of the device, all as hereinafter fully described and then pointed out in the claims.

I have illustrated a type of my invention in the accompanying drawings, wherein—

Figure 1 is a perspective view of my draft attachment mounted upon an ordinary gas-burner, which is shown as emitting a flat flame. Fig. 2 is a cross-section taken on a plane extending centrally through the attachment.

Referring to the drawings, in which like numbers of reference designate like parts, 2 is an ordinary gas-burner, having a slit mouth 3, which produces a flat flame 4, as shown in the drawings. Upon this burner is mounted a body or hood comprising two long sides 5 and 6, which converge upwardly, and two vertical ends 7 and 8, making a four-sided hood which is A-shaped in cross-section. Preferably the entire base of the hood is open, as shown at 9, and the top is formed with a comparatively-narrow slit or opening 10, extending from one end to the other. Each of the long sides at its center is formed with an outwardly-bowed part 11, which together make up a suitable opening for the upward passage of the cylindrical gas-burner 2. This

hood being made preferably of a suitable metal is somewhat resilient, so that the two long sides clamp the burner with a slight spring-pressure, and thereby retain it in fixed position on the same. I, however, preferably provide the hood with a centrally-located collar or holder 12, fixed across the base thereof and provided with upwardly-extending spring fingers or tubes 13 for receiving the burner and to give additional stability to the attachment when placed upon it.

This draft attachment is placed over the burner 2, so that the same projects up through it, as shown in Fig. 1, and the attachment is adjusted on the burner until the draft slit or opening 10 in the top or crest of the hood lies in the plane of the flat flame. When so placed and the flame is on, a considerable draft is created through the upwardly-converging draft-chamber within the hood lying upon each side of the burner, and this draft making a forcible exit from the crest or top of the hood throws a steady and uniform stream of air upwardly against the flame in the plane thereof, thereby increasing the air-supply and steadyng the flame. This increased air-supply increases in corresponding degree the illuminating power of the flame and decreases in corresponding degree the smoke or carbon deposit emitted from the flame.

It will be observed that the shape of the hood may be changed as desired, so long as provision is made for directing upwardly against the flat flame a steady stream of air in the same plane as the flame. I therefore wish to be understood as not limiting my invention to the specific construction herewith shown, as it is obvious that various modifications may be made in the same without departing from the spirit of the invention.

Having thus described my invention, what I claim, and desire to secure by Letters Patent, is—

1. A draft attachment for a gas-burner producing a so-called "flat" flame, the same consisting in a body or hood adapted to be placed centrally upon the burner beneath the mouth thereof and provided with one or more draft-chambers, a narrow elongated opening leading from said draft-chamber through the top of the hood at opposite sides of the burner to lie in the plane of the flame and beneath the

same when adjusted upon the burner, substantially as and for the purpose set forth.

2. A draft attachment for a gas-burner producing a so-called "flat" flame, the same consisting in a body or hood provided with one or more upwardly-converging draft-chambers and having a substantially-central opening for the burner to extend through, a narrow elongated draft-opening in the top of said hood upon opposite sides of the central burner-opening and communicating with said draft-chamber and adapted to lie in the same plane as the gas-flame and beneath the same when the attachment is adjusted upon the burner, substantially as and for the purpose set forth.

3. A draft attachment for a gas-burner producing a so-called "flat" flame, the same comprising a hood having upwardly-converging long sides and closed at its ends and having a broad opening at the base and a comparatively-narrow elongated opening along the top for the exit of the draft, a substantially centrally located opening for the passage of the burner said draft-opening lying upon two

opposite sides of said burner-opening and 25 adapted to stand in the same plane with the flame when the attachment is adjusted on the burner, substantially as and for the purpose set forth.

4. A draft attachment for a gas-burner producing a so-called "flat" flame, the same comprising a hood A-shaped in cross-section and having a wide opening at the base and a narrow opening along the top, the ends of the hood being closed, the central portion of the 30 hood being slightly bowed out on the two opposite sides for receiving a cylindrical burner, and a collar or holder mounted centrally within the hood for the passage of the burner, substantially as and for the purpose set forth.

40 In testimony whereof I have hereunto affixed my signature in the presence of two witnesses.

THOMAS J. BUSH.
